UNITED STATES PATENT OFFICE.

WILLIAM S. WESTON, OF CHICAGO, ILLINOIS.

RAILWAY-TIE PLATE.

No. 914,092.

Specification of Letters Patent.

Patented March 2, 1909.

Application filed December 30, 1907. Serial No. 408,542.

To all whom it may concern:

Be it known that I, WILLIAM S. WESTON, a citizen of the United States, and a resident of Chicago, county of Cook, and State of Illinois, have invented new and useful Improvements in Railway-Tie Plates, of which the following is a full, clear, and exact description.

My invention relates to improvements in railway tie plates of the class that are interposed between the base of the rail and the tie, stringer, or other substructure on which the rail is thereby better held and supported; and has for its primary object the provision of new and improved means integral with the tie plate for preventing the longitudinal movement or "creeping" of the rail over the plate and substructure. The novel means for attaining this function in a tie plate, together with other novel features of improvement, are hereinafter described, clearly illustrated in the accompanying drawings which form a part of this specification, and particularly pointed out in the claims.

In the preferred form of my invention, and as illustrated, I accomplish my full purpose by means of a tie plate provided with an over-hanging resilient lip on one side adapted to bear on and clamp one of the rail base flanges, and, on the other side, with a serrated or roughened shoulder adapted to bear against the edge of the other rail base flange. The tie plate also preferably has a downwardly projecting lug adapted to engage the tie or substructure.

In the drawings, Figure 1 is a plan view of my invention in position of service; Fig. 2 is a vertical cross section of the tie plate and rail on the line 2—2 of Fig. 1; Fig. 3 is a cross section of the rail and plate showing how the plate is put in position; Fig. 4 is an edge view of the plate with a dotted outline of the rail to show the relative shape of the overhanging lip when not in position on the rail; Fig. 5 is an enlarged scale plan of one corner of the plate, showing more perfectly the serrated shoulder; Fig. 6 is a partial sectional elevation on the lines 6—6 of Figs. 4 and 5; Fig. 7 is a section on the line 7—7 of Fig. 5.

Similar letters refer to similar parts in the several views.

Referring to Figs. 1 and 2, A is the tie plate, T the tie or substructure, and R the rail.

The tie plate A is provided upon its upper face with two integral abutments B and D,

which are arranged to receive and grip the base of the rail between them. In the particular form of the invention illustrated, the abutment B is in the form of an overhanging lip or leaf integral with the plate and forming a recess C in which one flange of the rail base is placed. The abutment D is in the form of a shoulder formed upon the upper surface of the tie plate and is arranged to engage the other flange of the rail base. The shoulder D is provided with teeth or projections E adapted to indent the flange when the rail is in position.

A lug or rib F dependent from the under side of the plate, Figs. 2, 3 and 4, is adapted to be embedded in the tie when in position. The rail is held down to the tie or substructure by means of spikes S, S. In the construction shown, the spikes are driven through holes S' in the plate, the spike on the side of the shoulder D taking effect directly on the rail while the spikes on the side of the lip B take effect indirectly by holding the plate down, the lip B being depended upon to hold down that side of the rail base.

To get the best results with my invention, the plate should be made from a resilient metal, such as spring steel, with the jaw C slightly closed up when in the free position, as shown in Fig. 4.

To set the plate, it is first slipped on the base of the rail to a position approximating that shown in Fig. 3, when it is driven to position by striking on the edge H, causing the lip B to spring up, as indicated in Fig. 3, until the shoulder D clears the opposite base flange. The lip then recovers a part of its distortion and the plate takes a position approximating that shown in Fig. 2, with the edge of the base flange bearing against the teeth E. E. The first load on the rail, or the driving of the spikes, then brings it down to a full seat on the plate and causes the teeth to become wholly or partly embedded in the edge of the flange. It should be noted that the teeth E are preferably provided with vertical beveled edges, are widest at the bottom of the shoulder D and taper to a point at the upper edge of the shoulder.

Attention is called to the clearance space J, Figs. 2 and 4 between the edge of the base flange and the bottom of the jaw C. This space is made to allow for a variation in the width of rail bases of nominally the same section. In some instances, the width of the space may be greater than the depth of the

teeth E. E, and in case the plate is driven on hard enough to bring the flange to the bottom of the jaw, the opposite flange will clear the teeth. For such cases the reaction of the 5 silent lip B on the sloping upper surface of the base flange is depended upon to restore and maintain contact against the teeth, while the wearing action between the rail and the plate, due to taking the load on and off 10 the rail, is depended upon to cause the teeth to become more or less indented in the rail.

As stated at the beginning of these specifications, the primary object of my invention is to provide a tie plate which will prevent 15 longitudinal movement or "creeping" of the rail over the substructure. In the best accomplishment of this object with the tie plate illustrated and described, the resilient lip B and the serrated or tooth shoulder D grip the 20 rail base to prevent movement of the rail over the plate, while the dependent lug F and spikes S engage the tie to prevent movement of the plate over the tie.

While the combination of the four elements, the resilient lip B, the serrated shoulder D, the dependent lug F, and the spikes S, gives the greatest power for holding the rail, yet I do not wish to limit myself to this exact 25 combination. It is unnecessary that the grip between the rail and the tie should be positive. In fact it is preferable that the grip yield before the tie begins to move on the ballast or other substructure on which it is bedded. I may, therefore, by the use of a 30 greater number of tie plates, depend upon the friction contact of the jaw C on the rail to hold it from "creeping", and dispense with the teeth E. E. Or the lip B forming the jaw C might be much smaller, that is, merely a 35 shoulder having little or no frictional grip on the rail; in which case I would depend upon the indentation of the teeth E. E in the edge of the rail base.

When spikes are driven through holes in the 45 tie plate as shown, I may dispense with the lug F and depend upon the spikes for holding the plate against transverse movement on the tie. On the other hand, by the use of the lug F I may dispense with the spikes, so far 50 as the functions of my invention are concerned. For the spikes are used to hold the rail down and against transverse movement, and may be placed outside the tie plate or replaced by any other known means for so 55 holding the rail, and yet, my device would fulfil its purpose of securing the rail against longitudinal movement.

An important and novel feature of my invention also consists in the improved means 60 provided for holding the rail against the side thrust of the load, or against a tendency of the rail to buckle under longitudinal pressure. This purpose is accomplished by the combination of the shoulder D and jaw C, 65 which makes it impossible for the rail to

move in any transverse direction without taking the plate with it, and thereby bringing into effect the full holding power of all the spikes passing through the plate.

Another feature of novelty consists in the 70 combination of a tie plate and an anti-creeping device in one integral piece. By this feature I am enabled to reduce the number of parts to be used in track equipment and thereby accomplish a saving in primary and 75 maintenance cost.

Attention is called particularly to Figs. 2, 3 and 4 to note that the device is a single piece clamp which does not require the use of a separate spike, bolt or key. When sprung 80 into the position shown in Fig. 2, the seating of the rail relative to the plate is maintained by the weight of the rail or by the resilient action of the lip B and the clamping effect is accomplished independent of the spike S on 85 the left of Fig. 2.

It should be noted that the improved device constitutes a combined tie plate and clamp, and that the lips B and shoulder D thereof constitute abutments between which the rail base is gripped. In the particular form of the invention illustrated, the resilient lip B is so shaped that the space bounded by it and the shoulder D is smaller than the rail base, as indicated in full lines in Fig. 4. 90 The rail base, however, can be mechanically forced into position between the shoulder and the lip, since the latter is resilient and is distorted to enlarge or expand the space which receives the rail base. The resilient portion 95 or lip B will then tend to react and will force the rail against the shoulder D, as described, so that the rail base will be securely gripped between the abutments of the anti-creeping clamp or tie plate. Moreover, even if the bases 100 of the rails vary slightly in size, as is sometimes the case, they will be securely gripped, since the lip or portion B is sufficiently 105 resilient to take care of any such variation.

While the invention is preferably in the form 110 of a tie plate, as set forth, it comprises broadly an anti-creeping device or clamp for railway rails having abutments for gripping the opposite edges of the rail base and forming a contracted space slightly smaller than 115 the rail base, a portion of the device being resilient and yielding, so that it can be mechanically sprung on to or forced into engagement with the rail base and the latter securely gripped between the abutments. It is 120 obvious therefore that the details of form and structure set forth may be widely varied without departure from the essentials of the invention.

Having described my invention what I 125 claim as new and desire to secure by Letters Patent, is:—

1. An anti-creeping device for railway rails formed of resilient metal and having integral abutments arranged to form a contracted 130

- space slightly smaller than the rail base, a portion of said device being resilient and yielding to permit the forcible seating of the rail base between said abutments.
5. 2. An anti-creeping device for railway rails comprising a clamp adapted to grip the opposite edges of the rail base when sprung into position thereon, said clamp having a resilient portion for holding it in position upon the rail.
10. 3. A railway, anti-creeping tie plate adapted to be interposed between the rail and the tie and having a depending lug or lip for engaging the tie, said tie plate having integral abutments arranged to form a contracted space slightly smaller than the rail base, a portion of said device being resilient and yielding, whereby the rail base will be securely gripped when seated in said space.
15. 4. A railway rail fastening device comprising a plate adapted to be interposed between the rail and the tie and to be secured by spikes or bolts to the tie, and having integral abutments arranged to form a contracted space slightly smaller than the rail base, a portion of said plate being resilient and yielding, whereby the rail base will be securely gripped when seated in said space.
20. 5. An anti-creeping device for railway rails comprising a combined tie-plate and clamp adapted to be secured to the tie and to grip the edges of the rail base when sprung into position thereon, said combined tie-plate and clamp having a resilient portion for holding it in position on the rail.
25. 6. A railway tie plate having oppositely disposed abutments on its upper surface between which the rail is to be seated, and a series of sharp ridges arranged vertically on and projecting from the inner face of one of said abutments, the said abutments being set so close as to cause the edge of the rail base to become indented by the said ridges in the process of its seating.
7. A railway rail anti-creeping device comprising a tie plate for supporting the rail, means for attaching the plate to the tie, a resilient jaw on one side of the rail, and a shoulder on the other side of the rail; the said jaw and shoulder being formed integral with said plate and adapted to grip the rail base between them when sprung into position beneath the rail.
45. 8. In a railway tie plate having abutments on its upper surface adapted to be in juxtaposition to the rail base edges, the combination with said abutments of a series of sharp ridges arranged vertically on and projecting from the inner face of the abutment toward said rail base edge; the said ridges being larger at the base of the abutment and diminishing in projection and width toward the top of the abutment.
55. 9. An anti-creeping device for railway rails comprising a combined tie plate and clamp having integral abutments on its upper face arranged to form a contracted space slightly smaller than the rail base, one at least of said abutments being resilient and yielding, whereby the rail base can be forced to a seat in said space and be securely gripped by said abutments.
60. 10. A railway tie plate having oppositely disposed abutments on its upper face arranged to form a contracted space slightly smaller than the rail base, a portion of said plate being resilient and yielding, whereby the rail base can be forced into said space and gripped between said abutments, one at least of said abutments having a series of gripping teeth projecting from the inner face thereof.
75. 11. A railway tie plate having oppositely disposed abutments on its upper face arranged to form a contracted space slightly smaller than the rail base, a portion of said plate being resilient and yielding, whereby the rail base can be forced into said space and gripped between said abutments, one at least of said abutments having a series of gripping teeth projecting from the inner face thereof.
